UNITED STATES PATENT OFFICE

JACOB P. FISCHER, OF BROOKLYN, NEW YORK, ASSIGNOR TO EUGENE, LTD., OF NEW YORK, N. Y., A CORPORATION OF NEW YORK

CLIP AND SCALP PROTECTOR

Application filed January 4, 1929. Serial No. 330,242.

The invention relates to a known type of device used in hair waving, which is clamped about the inner end of the cover of a pad surrounding the curled lock of hair, for the purpose of sealing the end of the pad next to the scalp to avoid the escape of steam on the scalp. Such known devices consist each of a pair of curved plates hinged together at one pair of extremities, and provided at the other pair of extremities with automatic snap-engaging elements cooperative at a series of positions, when these extremities are pressed inward so as to pass one over the other, in order to hold the clip clamped about the cover and the lock of hair.

The plates of these devices often become bent so that the snap engagement fails to hold. The resilience of the metal of the plates, plus some possible looseness in the hinge, being relied upon to afford the give necessary for the snap action, the holding soon becomes insecure, even though in the beginning the operation may be comparatively stiff. The opening of the clips, after the heat treatment has been completed, is also inconvenient, and often causes discomfort to the patron.

The object of this invention is to make a device of this character which is more durable, in which the holding is rendered more secure, and in which the operation of opening the clip is facilitated. The manner in which these ends are attained can best be explained in connection with a description of the preferred embodiment illustrated in the accompanying drawings, wherein:

Fig. 1 is a sectional view illustrating the application of the device to a lock of hair and to a pad;

Fig. 2 is a plan view of the device;

Fig. 3 is a side elevation of the same;

Fig. 4 is a front elevation; and

Fig. 5 is a section taken on the irregular line 5—5 of Fig. 2.

The device comprises a pair of generally flat, thin, curved shield plates 2, 3, the curved inner edges 4 of which enclose an opening 5 of variable size when the plates are moved inward one over the other.

One pair of extremities are superposed and

are connected, in part, by a stud 6, which is passed through holes pierced in these extremities. The stud is preferably riveted to the extremity of one plate, in this instance the plate marked 2. It projects above the extremity of the other plate, and is provided at a distance from this plate with a head 7. Between this head and the face of the plate 3 a stiff compression spring 8 is confined, the action of this spring being perpendicular to the plates so as to hold the superposed hinged extremities firmly together, but with some capacity for slight yielding in the spring.

One of the plates is formed in its other extremity with a low struck-out latching projection 9 having its forward side formed on a slope and its rear or holding side comparatively abrupt. The cooperating extremity of the plate 3 has a series of openings or recesses 10 into which the projection 9 on the face of the plate 2 will snap successively when these extremities are moved over each other in the closing direction, thereby locking the clip against opening out and causing it to be clamped against the back or cover of a pad 11 surrounding the lock of hair. Fig. 1 shows it so applied, *a* being the lock of hair, *c* the curler on which the lock of hair is wound, *d* being the moistened pad, and *b* the impervious or non-porous back or cover of the pad.

One of the plates is offset or bent intermediate its ends, as shown at 11, so that its extremities lie in different planes, causing one extremity to underlie and the other extremity to overlie the other plate. This reversal of superposition between the hinged extremities and the snap-locking extremities materially improves the locking action and renders the clips stronger and more durable. It is of particular advantage in connection with the spring tensioned hinge.

In the particular embodiment shown, it will be observed that the hinged extremity of the plate 2 underlies the hinged extremity of the plate 3, whereas the free extremity of the plate 2 overlies the free extremity of the plate 3 when the clip is closed. One of the effects of this is to cause the hinged extremities of the plate to fulcrum against each other and to draw the head of the stud 6 against the

spring 8, increasing the compression of the latter.

The locking elements 9, 10 coact between overlapping portions of the plates in such manner that as these portions slide over each other from one locking position to another the faces are forced apart in a direction perpendicular to the plates against resilient resistance which presses the faces together. The nature of the locking means may be said to be such that torsional stress is imposed on the clip.

The slight yielding of the stiff spring in the hinge results in an improved locking action, which is more secure and longer wearing than is the case in those forms of device in which the resilience of the plates alone, or such resilience aided by undesirable looseness in the hinge, is relied upon. With this invention, the plates can be made of stiffer material and distortion of the plates which would render the device useless need not occur, the strain being largely taken by a separate spring adapted to withstand it and to preserve its resilience.

Another feature of the invention has to do with the knobs or finger pieces 12 which protrude from the outer corners of the free extremities of the plates. The improvement in this respect consists in skewing the finger pieces so that they are diagonal, both in the same sense, to the planes of the plates. The direction of the inclination is such that, when effort is applied to the pieces 12 to open the clip, there is a resultant which relieves the pressure between the superposed snap-engaging extremities, thereby making it easier to open the clip.

What is claimed as new is:

1. A clip and scalp protector for use in connection with hair waving appliances, comprising a pair of thin curved plates hinged together at one pair of superposed extremities and provided at their other extremities with automatic snap-engaging elements cooperative at a series of positions when these extremities are pressed inward so as to pass one over the other, said elements comprising a projection on the face of one of the plates and a series of recesses in the other plate, the coaction of which is such that the plates are forced apart in a direction perpendicular to the plates as these portions slide over each other from one locking position to another, characterized in that the first-mentioned pair of extremities are hinged together by a headed pin which projects above the plates and that a stiff compression spring is interposed between the head of the pin and the face of one of said extremities, the action of said spring being perpendicular to the plates.

2. A clip and scalp protector as set forth in claim 1, further characterized in that the superposition of each pair of extremities is the reverse of that of the other pair.

3. A clip and scalp protector as set forth in claim 1, further characterized in that the superposition of each pair of extremities is the reverse of that of the other pair and that one of the plates is formed with an offset intermediate its extremities.

4. A clip and scalp protector for use in connection with hair waving appliances, comprising a pair of thin curved plates hinged together at one pair of superposed extremities and provided at their other extremities with automatic snap-engaging elements cooperative at a series of positions when these extremities are pressed inward so as to pass one over the other, said elements comprising a projection on the face of one of the plates and a series of recesses in the other plate, the coaction of which is such that the plates are forced apart in a direction perpendicular to the plates as these portions slide over each other from one locking position to another, characterized in that the plates are provided with projecting operating pieces which are set diagonally to the planes of the plates both in the same sense, so that effort applied to the finger pieces to open the plates about the hinge causes a resultant which relieves the pressure between the superposed snap-engaging extremities.

JACOB P. FISCHER.
